CALCULATING MACHINE

Robert L. Muller, Detroit, Mich., assignor to Burroughs Adding Machine Company, Detroit, Mich., a corporation of Michigan

Application August 9, 1935, Serial No. 35,433

5 Claims. (Cl. 235—60)

This invention relates to a calculating machine, and it is concerned particularly with automatic controls for conditioning the machine for different types of operation.

5 Calculating machines are usually conditioned for different operations by means of special keys, or levers, or by having a paper carriage actuate certain parts to condition the machine automatically. One of the difficulties with having the 10 paper carriage actuate the controls is that it places a load upon the carriage that interferes with its proper operation. For example, if there are no controls to be actuated in several columns of the carriage, the carriage will move freely and 15 rapidly in these columns but, if, in other columns there are a number of controls to be actuated, and this number varies, the carriage is loaded up in varying amounts and will move slowly, or sluggishly, or erratically. The present invention 20 has been devised to overcome this difficulty.

The general object of the invention is to provide an improved automatic control for conditioning a calculating machine for different operations.

25 More specifically, the object of the invention is to provide a machine in which a function indexing means is automatically set after which this means is sensed by a means that conditions the machine for the desired operation.

30 A further and more particular object is to provide improved controls for governing the movement of the paper carriage of a calculating machine.

Other objects and advantages of the invention 35 will appear from the following specification and drawings.

An embodiment of the invention is shown in the accompanying drawings, in which:

40 Fig. 1 is a right side elevation of a machine with the invention applied thereto, certain parts being cut away to show others more clearly, and with the parts in normal position;

45 Fig. 2 is a left side elevation, some of the parts being cut away to show others more clearly, and the parts being shown in normal position;

Fig. 3 is a rear elevation showing particularly the manner in which the paper carriage is controlled and some of the parts that are set by said carriage;

50 Fig. 4 is a detail right side sectional elevation of certain portions of the machine at the lower rear side, the view showing particularly the indexing means in the position it occupies before the motor bar has been depressed;

55 Fig. 5 is a view similar to Fig. 4 showing the

parts in the position they occupy after the motor bar has been depressed but before the machine has operated;

Fig. 6 is a view similar to Fig. 5, except that the parts are shown in the position they occupy 5 at the extreme end of a forward stroke of machine operation and just after the printing mechanism has operated;

Fig. 7 is a left side elevation and section certain of the controls, taken near the rear of the 10 machine, the view showing the parts in the position they occupy after the motor bar has been depressed but before the machine has started to operate;

Fig. 8 is a perspective view showing particularly 15 the tabulating mechanism associated with the paper carriage;

Fig. 9 is a view of the carriage return mechanism, the view being taken from the front and showing the manner in which this return mechanism is used with the present invention; and 20

Fig. 10 is a perspective view of certain portions 25 of the indexing and sensing means.

Fig. 11 is a view showing a sample of one form 30 of work that may be performed with the invention.

The invention is shown applied to a Burroughs calculating machine of a type that is well known so that a detailed description is not necessary. It will be understood that the invention can also 35 be used with other types of machines.

General machine construction

The machine is provided with a plurality of 35 depressible amount keys 10 (Fig. 1) upon which items may be entered after which the machine can be operated by depressing a motor bar 11 that causes a motor 12 to give the machine a cycle of operation which includes a forward and a return stroke. During this cycle, the machine performs certain functions depending upon how it is 40 conditioned.

The amount keys control the position of actuator racks 13 which mesh with large gears 14, with which a main register 15 and two multiple 45 registers 16 and 17 are adapted to cooperate.

A printing mechanism including the type bars 18 is operated near the end of the forward stroke in the cycle of machine operation to print the items entered or the calculation performed. 50

The machine is provided with a platen P about which paper may be held in printing position relative to the printing mechanism. Provision is also made for causing printing to occur in different columns on the paper. This is accom- 55

plished by supporting the platen on a travelling paper carriage 20 controlled by a tabulating mechanism of which portions are shown in Fig. 3 and which will be described in more detail later. 5 This tabulating mechanism is normally operated during the latter part of each cycle of operation of the machine to release the carriage for movement to the next column under the urge of a spring 21 (Fig. 3). The carriage can be returned 10 automatically by power through a carriage return mechanism 22 of the type described in Rinsche Patent No. 1,580,534.

Function indexing means

15 Instead of having the paper carriage condition the machine to perform different functions, the carriage merely indexes an indexing means which is relatively light and which places very little load upon the carriage. This makes possible 20 a lighter and faster moving carriage and one that may be started and stopped quickly in either direction. Also, the load on the carriage remains the same for all its movements.

The indexing means is in the form of a rotatable drum 30 (Fig. 2) mounted upon a shaft 31 carrying a worm wheel 32 meshing with a worm 33 fixed to a shaft 34. Fixed to the end of shaft 34 is a gear 35 that meshes with a rack 36 (Fig. 3) fixed to the paper carriage. It will thus be 30 seen that the drum 30 rotates as the carriage is moved, and occupies various indexed positions, or stations, depending upon the columnar position of the carriage.

The indexing drum has a series of cross members 37 (Fig. 3) to which are detachably connected a series of indexing, or abutment, stops of which five are shown on the cross bar illustrated in Figs. 3 and 10, numbered 40, 41, 42, 43 and 44. These stops are of various lengths 40 and the number of them, their location, and the height of the stops in the various positions can be changed to suit the requirements. In each of the columnar positions of the carriage, the indexing drum is brought to a position, or station, 45 where one of the cross bars, with the appropriate stops on it, is in active, or indexed, position so that the stops may be "sensed," or "felt" by a sensing or a function conditioning means to be described later.

50 In other words, an indexing means is set in accordance with the conditioning of the machine for columnar printing, after which the indexing means is sensed by a means which, in the form of the invention disclosed, is a mechanical "feeling" 55 mechanism.

Sensing means

As mentioned, the machine is conditioned to 60 perform different functions by having a mechanism feel, or sense, the indexing means. The term "function" as used herein, is not intended to include only calculating functions such as addition or subtraction, but also functions such as repeat operations of the machine, skip-tab operations, control of the printing mechanism, and similar functions.

For the purpose of sensing the indexing means, a series of vertically movable members, or links, are provided, five being shown in the present embodiment of the invention and numbered 46, 47, 48, 49 and 50, as shown in Figs. 3 and 10. These sensing members are guided at their lower ends by a plate 51 (Fig. 2) and, at their upper ends, are connected to arms 52 of which there is one for each of the members. The arms 75 52 are pivoted on a stationary shaft 53 near the

rear of the machine. Those sensing members are normally held in elevated position by means of a shaft, or bail, 55 that engages the undersides of the arms. The shaft 55 is carried by side arms 56 pivoted on the shaft 53 and a spring 57 serves to urge the bail in a clockwise direction as viewed in Fig. 2. Also, springs 58, of which there is one attached to each of the arms 52, serve to urge the arms in a clockwise direction so that, not only the controlling bail 55 but 10 also the arms 52 with the sensing members 46-50 are urged clockwise to a "feeling" or "sensing" position.

The bail 55 is held upward by means of a lever 60 (Fig. 4) pivoted on a shaft 61. The rear end 15 of this lever is positioned under the bail 55 and its forward end is connected to a downwardly extending link 62 whose lower end has a slot 63 in which is positioned a stud 64 carried by a lever 65 pivoted on a stationary stud 66. The lever 65 20 is urged counterclockwise as viewed in Fig. 4 by a relatively strong spring 67 connected to it by plates 68, but it is normally held against movement by the engagement of a stud 70 on the lever with the edge of a cam 71 fixed to a 25 shaft 72 that is rotated one revolution during each cycle of operation of the machine. Pivotally connected to the stud 64 on the lever 65 is a second link 73 whose upper end has a stud and slot connection 74 with the link 62. The link 30 73 carries a latch 75 urged counterclockwise as viewed in Fig. 4 by a spring 76 to cause a lug 77 on the latch to engage over a shoulder 78 on the link 62.

With the parts in the position of Fig. 4, the 35 bail 55 tends to urge the lever 60 clockwise, which tends to pull the link 62 upward, but the latter cannot move upward because it is held by the latch 75 carried by the link 73 connected to the lever 65 that is held against upward movement 40 by the relatively strong spring 67. Accordingly, in this position of the parts, which is the normal position, the bail 55 is held upward and the feeling or sensing members 46-50 remain elevated in inactive position. 45

The bail 55 is released, in the embodiment of the invention shown, as an incident to the conditioning of the machine for a cycle of operation by means of the motor bar 11.

Referring to Fig. 1, the motor bar 11 is connected to the pivoted levers 80 and 81 in the usual manner so that the lever 80 is rocked counterclockwise as viewed in Fig. 1 when the motor bar is depressed. Movement of this lever, acting through spring 82, tends to raise the long motor control link 83 that controls the clutch 84 and causes the motor to give the machine a cycle of operation. The rear end of lever 81 has a stud and slot connection with an arm 85 fixed to a shaft 86. The shaft 86 extends across the 60 machine and, near the center of the machine, another arm 87 is fixed to it. The latter is pivotally connected to a downwardly extending link 88 whose lower end (Fig. 4) is connected through a spring 89 to one arm 90 of a bell crank lever 65 pivoted at 91. The other arm 92 of this bell crank lever is connected to a link 93 provided with a bent end positioned in front of a stud 94 carried by a pass-by pawl 95 pivoted on the latch 75 and urged counterclockwise by a spring 96. 70

From this, it will be observed that, when the motor bar is depressed, the link 88 is raised which rocks the bell crank 90-92 counterclockwise as viewed in Fig. 4, and pulls the link 93 rearwardly to move the latch 75 out of engagement with the 75

shoulder 78 on the link 62. When this occurs, the link 62 is free to move upward. This means that the lever 60 is free to rock clockwise and that the bail 55 can move downward under the urge of its spring. The net result is that, when the motor bar is depressed, the bail 55 moves downward and the feeling members 46-50 move to their sensing positions. The position of the parts after the motor bar has been depressed but 10 before the cycle of machine operation has started is shown in Fig. 5.

It is desirable to have the members 46-50 sense the indexing means before the machine starts to operate and, since these members are released by depression of the motor bar, provision is made for preventing depression of the motor bar from causing a cycle of machine operation until the sensing members have moved to sensing position and conditioned the machine. Referring to Fig. 20 1, a latch lever 100 is pivoted adjacent the motor control link 83, the latch lever being urged counterclockwise as viewed in Fig. 1 by a spring 101, but being held in the position of Fig. 1 by a cam lever 102 that engages a stud 103 on the upper 25 end of the latch lever. The lower end of the latch lever is positioned to engage a shoulder on the link 83 to prevent upward movement of said link to cause a cycle of machine operation until the latch lever 100 is rocked counterclockwise 30 from its Fig. 1 position. The cam lever 102 is fixed to a shaft 104 to which is also fixed an arm 105 connected to one end of a link 106 whose lower end is connected to a bell crank lever 107 urged counterclockwise as shown in Fig. 1, by a 35 spring 108.

The rear arm of the bell crank lever 107 is positioned under the bail 55 that controls the sensing members 46-50 inclusive. When the bail 55 is moved downwardly, it rocks the bell crank 40 107 clockwise against the tension of spring 108 and moves the cam lever 102 to release the lever 100, for movement to released position under the urge of its spring. This releases the motor control link 83 and its spring 82 then moves it upwardly to cause the machine to be given a cycle 45 of operation. But, since this cannot happen until the bail 55 moves downward, which action releases the sensing members 46-50 the cycle of machine operation does not occur until the sensing members have moved to condition the machine.

The mechanism above described is returned to normal position during a cycle of operation of the machine as follows: Referring to Fig. 4, 55 the shaft 72 is given a complete revolution during each machine cycle. This shaft corresponds to the shaft in Rinsche 1,580,534 to which the crank 48 of said patent is attached. This shaft makes a complete revolution at about the rate 60 of 200 strokes per minute whereas the machine, owing to the spring connections with the drive and the spring return stroke operates at the rate of about 125 strokes per minute. During the forward stroke of the machine, a raised portion 65 of cam 71 engages the stud 70 on lever 65 and rocks the lever to the position of Fig. 6. As it moves to this position, the link 73 is moved upwardly which moves the latch 75 upward and moves the stud 94 out of the control of the link 73. The latch 75 then moves counterclockwise 70 under the urge of its spring and the lug on said latch moves over the shoulder 78 on the link 62. The movement of the lever 65 by cam 71 retensions the spring 67, and when the stud 70 moves off of the high portion of the cam, the spring 75

tends to pull the link 73 downward. Since this link is now latched to the link 62, the latter tends to move downward which would rock the lever 60 counterclockwise as viewed in Fig. 6 and raise the bail 55 to raise the sensing members 46-50 5 to normal. But it is not desired to have the sensing members 46-50 moved upward so early in the cycle of machine operation, owing to the fact that they control certain other parts that will be presently described. Accordingly, a latch 10 110 is provided (Fig. 6) which is urged counterclockwise by a spring 111 so that when the link 73 is moved upward to its Fig. 6 position, the latch 110 automatically moves over a stud 112 on the link and latches the link in Fig. 6 position. 15 The latch is released during the return stroke of the machine by a pass-by pawl 113 carried by a sector 114 on a shaft 115 that is first rocked clockwise from the position of Fig. 4 to that of Fig. 6 and then returned counterclockwise to normal. 20 The shaft 115 is the shaft ordinarily known as the "800 shaft" in the Burroughs machine, the same being so numbered in the patent to Burroughs 504,963. During the counterclockwise movement, that is, during the return stroke of the machine, the pawl 113 engages a stud 116 on the latch 110 and moves the latter to release link 73 whereupon the links 73 and 62 are moved downwardly and the bail 55 is restored to normal 25 to restore the sensing members 46-50 to normal. 30

When the bail 55 is restored to normal, the bell crank 107 (Fig. 1) is released whereupon its spring 108 rocks it counterclockwise and restores the cam lever 102 to the position of Fig. 1 to thereby restore the latch lever 100 to active position. 35

In this manner, the function indexing means is sensed automatically prior to an operation of the machine; the machine is conditioned to perform predetermined functions depending upon 40 the columnar position of the carriage and the arrangement of the indexing stops on the drum 30; the machine is operated; and, during the cycle of operation, the sensing means is restored to normal to free the indexing means to permit it to 45 move easily when the carriage moves to the next column. Various functions may be controlled but, in order that the operation of automatic conditioning the machine may be clear, five illustrative functions will now be described. 50

Control of main register

Controls are shown for conditioning the main register, sometimes called the "crossfooter," for addition, subtraction, or "non-add". 55

Referring to Figs. 2 and 7, a four-armed lever 120 is pivoted at 121. Its upper arm, to which the reference numeral 120 has been applied, is connected to the lower end of a manually controllable lever 122 pivoted at 123. This 60 lever has three positions. Its central position is a "non-add" position; its rear position shown in full lines in Fig. 2 is an "add" position; and its forward position, shown in dot-dash lines in Fig. 2, is a "subtract" position. The lever is 65 urged counterclockwise as viewed in Fig. 2 by a spring 124 connected to four-armed lever 120, which spring thus tends to move the parts to "add" position.

The forward arm 125 of the four-armed lever 70 120 (Fig. 7) is connected to a suitable mechanism 126, which has not been shown in detail, for controlling the main register 15 with respect to its non-add, add and subtract operations. 75

The rear arm 127 of the four-armed lever 120 is positioned under a stud 128 carried by the sensing member 46 which extends upward and is bent slightly forward for the purpose. When 5 the sensing member 46 moves downwardly under the urge of its spring 58, the four-armed lever 127-120 is rocked counterclockwise, as viewed in Fig. 7, to a position that depends upon the length of the indexing stop 40 that is in 10 active position at the time. If a long indexing stop is in position, the four-armed lever will remain in add position. If an intermediate stop is in active position, the sensing member will move down slightly and the four-armed lever 15 will be moved to "non-add" position. If a short stop 40 is in active position, the sensing member will move down a considerable distance to move the four-armed lever 127-120 to "subtract" position. The lever is also limited in its 20 "subtract" position by a stud 129 that contacts the edge of lever 120 (Fig. 7).

The four-armed lever is releasably held in any of its three positions by a detent 130 urged counterclockwise by a spring 131 to hold a stud 25 132 on the detent in engagement with one of several notches in the bottom edge of the arm 133 of the four-armed lever 120.

During a cycle of machine operation, the four-armed lever 120 is locked against movement until 30 after the machine operation has been completed. This is accomplished by means of the latch 135 (Fig. 7) movable into engagement with notches 136 in a sector 137 forming a part of the rear arm 127 of the four-armed lever 120. The 35 latch bail 135 is pivoted loosely on a shaft 138 and urged counterclockwise as viewed in Fig. 7 by a spring 139 connected at one end with a projection from one arm of the latch bail. The latch has a downwardly extending arm 140 carrying a stud which is positioned to be engaged by an arm 141 fixed to a shaft 142. The shaft 142 has another arm 143 fixed to it, which is controlled by a shaft 144, the latter being carried by arms 145 fixed to a shaft 146 that is 40 rocked during a cycle of operation of the machine. This shaft is what is ordinarily known as the "100 shaft" in the Burroughs machine, the same being so numbered in the patent to Burroughs 504,963, and numbered as shaft 47 45 in Rinsche 1,580,534. The arrangement is such that, during the first part of a machine cycle, the shaft 144 is rocked counterclockwise from the position of Fig. 7 and then returned clockwise during the latter part of the cycle. This 50 results in rocking the arm 141 clockwise at the beginning of a machine cycle to permit the latch 135 to move into engagement with one of the notches 136 where it remains until near the end of a machine cycle, whereupon the arm 141 is 55 rocked counterclockwise and the latch retracted from the notch.

Regardless of the position to which the four-armed lever 120 is moved, no matter whether manually or automatically, it is always returned 60 to normal "add" position at the end of a machine operation.

During each machine operation, a stud 150 (Fig. 7) carried by an arm 151 that first rocks counterclockwise and then returns clockwise with 65 shaft 115, engages the detent 130 and releases it. At the same time the arm 151 moves away from a stud 152 on a latch 153 pivoted on shaft 121 and urged clockwise by spring 154. As the 70 detent 130 is moved to released position, the latch 153 snaps over a lug 155 on the detent and holds 75

it in released position until near the end of the cycle of machine operation, that is, until after the locking latch 135 has been released, the sensing member 46 restored to normal, and the four-armed lever 120 thus released so that it 5 together with the manual lever 122 can be returned to "add" position by spring 124. After these events have occurred, the arm 151 engages the stud 152 and releases the latch 153 to permit the detent 130 to move to normal to hold 10 the four-armed lever in "add" position.

To summarize the action of the controls for the main register, they are normally in "add" position but may be manually conditioned for subtraction or non-adding by means of a lever 15 122. The controls are held momentarily in the position to which they are moved by a detent 130 and, then, during the cycle of machine operation, are locked against movement. Near the 20 end of the cycle of operation, the lock is released and, before the detent 130 becomes operative, the controls are automatically returned to "add" condition.

The controls are automatically conditioned for subtraction or non-adding by the sensing member 46 that moves the four-armed lever 120 to the desired position where it is temporarily detained by the detent 130. Then, during the cycle of machine operation, the four-armed lever is locked in position and, near the end of the cycle, 30 the sensing member is restored to normal, the lock released, and the controls returned to normal "add" condition.

Control of multiple registers

The registers 16 and 17 are controlled in much 35 the same way as the main register.

A four-arm lever 160 (Fig. 7) is provided for the register 16 and a similar lever 161 controls register 17. Each can be positioned by manual 40 levers 162 and 163 respectively which, however, are movable only to an "add" and "non-add" position, no provision being made for subtraction.

A separate detent, such as the detent 130 is 45 provided for each of the four-armed levers 160 and 161 and these detents operate in the same way as detent 130 except that the detent 130 for the main register is provided with a stud 164 extending under the detents for the registers 50 16 and 17, so that when the machine is operated and the detent 130 is moved clockwise to its released position where it is latched, the two detents for registers 16 and 17 are likewise moved and held. The four-armed levers 160 and 161 55 are locked against movement by the locking latch 135 in the same manner as the four-armed lever 120 for the main register is locked.

The four-arm levers 160 and 161 are automatically controlled by the sensing members 47 and 60 48 respectively (Fig. 3) in the same manner as the main register. The construction is slightly different for the registers 16 and 17, in that the sensing members 47 and 48 carry studs 166 and 165 (Fig. 10) that engage over the rearwardly 65 projecting ends of levers 167 and 168, respectively, pivoted at 169. The other ends of these levers are positioned to engage studs 170 and 171 on the four-armed levers 161 and 160 respectively.

The controls for the registers 16 and 17 are urged to "non-add" position rather than add position because, while it is generally desired to add items in the main register during each cycle of operation of the machine, it is not usu- 70

ally desirable to employ the multiple registers except in certain operations.

The four-arm levers 160 and 161 for the registers 16 and 17 are urged to "non-add" position by means of scissors devices (Fig. 7) of which there is one for each lever. Each comprises two members 172 and 173 pivoted on shaft 138 and straddling studs 174 or 175, as the case may be, carried by the respective four-arm levers 161 and 160. The two scissors members 172 and 173 are urged into engagement with their studs by springs 176.

Normally, each pair of scissors arms straddles a fixed stud 177 on the frame of the machine. When one of the four-arm levers 160 or 161 moves to "add" position, it is rocked clockwise and the stud 175 or 174 moves its respective scissors member 173 counterclockwise against the tension of spring 176. During a machine operation when the detent for the four-armed member is released and, after the locking latch 135 has been released, the four-armed member is restored to its "non-add" position by the spring urge on the scissors arm 173. The arm 172 will, of course, restore the four-armed member to normal when said member is moved in the opposite direction as is necessary in totaling operations which, however, will not be described.

30 Tabulating mechanism—Early release of carriage

Provision is made for causing the carriage to tabulate from one column to the other at an earlier point in the cycle of machine operation than is ordinarily the case.

The tabulating mechanism is operated by a cam 180 (Fig. 7) fixed to the main operating shaft 146 of the machine. This cam rocks a lever 181 whose rear end extends through the back plate of the machine where it has a fork and stud connection 182 with a slide 183. The arrangement is such that, during a cycle of machine operation, the slide 183 is first moved downwardly (Fig. 8) and then returned upward. This operates the line spacing mechanism (not shown in detail) to line space the platen during certain of the machine operations depending upon how the line spacing control is conditioned. The paper carriage supports a tabulating bar 184 (Fig. 3) carrying a plurality of tab stops 185, the bar being rockably mounted on the paper carriage and spring urged to the position shown in Fig. 8. In the different columnar positions of the carriage, the respective tab stops 185 abut against a block or abutment 190 (Fig. 8) which arrests the carriage in a columnar position corresponding to the stop, the carriage tending to move to the right in Fig. 8. As the machine is given a cycle of operation the tabulating bar carrying the tab-stop 185 is usually rocked to move the active tab stop above the abutment 190, whereupon the carriage moves to the next column, the arrangement being such that the succeeding tab stop 185 strikes the abutment 190 to arrest the carriage in the next column.

In the present case, instead of rocking the tabulating bar, the abutment is moved. Referring to Fig. 8, the slide 183 is provided with a pawl 192 having a shouldered end 193 engaging over a lug 194 on the abutment 190. The latter is pivoted at 195 and spring urged clockwise by a spring 196.

With this construction, as the machine starts to operate, the slide 183 moves downward and

the pawl 192 rocks the abutment 190 to move it out of the path of the active tab stop. Accordingly, as far as the tabulating mechanism above described is concerned, the carriage is released for movement at the beginning of a cycle of machine operation. However, it is not desired to have the carriage move at this time and means is provided for temporarily locking it in position.

Referring to Fig. 7, the lower rail 200 of the paper carriage is slotted at 201 to receive the lower edge of a pawl 202 pivoted at 203 and urged clockwise by a spring 204 connected at one end to the stationary bracket 205. The pawl is normally prevented from moving by a stud 206 carried by a rearwardly extending portion 207 of one of the arms 56 that support the bail 55 heretofore described. As long as the bail 55 is in its upper normal position, the pawl 202 is held inactive by stud 206 as shown in Fig. 2. It will be recalled, however, that, when the motor bar is depressed, the bail 55 is released and it moves downwardly before the machine starts to operate. When it moves, the stud 206 moves upward and releases the pawl 202 which is thereupon moved by its spring 204 into engagement with the carriage, as shown in Fig. 7, to hold the latter against movement. The carriage is thus prevented from moving to the next column, even though the tabulating mechanism has released it as above described.

Referring to Figs. 4, 5, and 6, it will be recalled that the bail 55 remains in its lower position during the first half of a cycle of machine operation and that, during this part of the cycle, the link, or slide, 73 is moved upward and latched in the position of Fig. 6. Also, that during the early part of the return stroke of the machine, the slide 73 is released and the release of this slide causes the bail 55 to be restored to normal. The restoration of bail 55 to normal causes the stud 206 (Fig. 7) to cam the latch 202 out of engagement with the paper carriage and the latter is thereupon released to move to its next columnar position. This release occurs early in the return stroke of the machine to give the carriage enough time to move to its next column by the time the cycle of machine operation has been completed.

The printing mechanism operates near the end of the forward stroke of a machine and hence the carriage is not released for movement until after the printing mechanism has operated.

As the tabulating pawl 192 (Fig. 8) moves downwardly, during the forward stroke of the machine, a stud 210 on the pawl engages a cam 211 (Fig. 3) which is prevented from rocking clockwise in Fig. 3 by a stud. This cam causes the pawl 192 to be pushed clockwise (Fig. 8) to move the shoulder 193 away from lug 194 to thereby release the abutment 190 which is thereupon freed to move back to normal under the urge of its spring 196. But the abutment does not return to normal until after the carriage starts to move to its next column because, when it was first released from the active tab stop 185, it moved to the left slightly (Fig. 8) so as to be under the active tab stop, which thus temporarily prevents its return. This lateral movement of the abutment is due to the fact that the abutment is carried by a stud 212 (Fig. 8) supported on a slide 213. This slide is connected to the lower end of a lever 214 (Fig. 3) pivoted at 215 and urged clockwise by a spring 216. The other end of lever 214 is connected to a dash

pot 217. When a carriage tab stop strikes abutment 190, the latter moves to the right slightly (Fig. 8) and the dash pot cushions the action, the spring 216 being tensioned. When the abutment is pulled down by the slide 163, as above explained, the spring 216 moves the slide 213 to the left and moves the abutment under the active tab stop.

10   *Control of tabulating mechanism for skip tabulation*

In addition to controlling various calculating functions of the machine, such as above described, another function of the machine that may be 15 automatically controlled is the tabulation of the carriage, that is, columnar printing.

The conditioning of the tabulating mechanism is controlled by the sensing member 49 (Figs. 3 and 10). The rear end of the arm 52 to which 20 the sensing member 49 is connected extends under one arm of a bell crank 222 best shown in Fig. 3. This bell crank is connected to a link 223 which is slideable on a stud 224 and provided with a downwardly extending projection 225 25 adapted to engage a slide 226 which is similar to the slide 92 shown in Muller Patent No. 1,942,216. Referring to Fig. 8, the slide 226 is yieldingly connected by a spring 227 to another slide 228 having a cam end 229 adapted to engage a cam 30 notch in the abutment 190. The arrangement is such that when slide 228 is moved to the right in Fig. 8, it cams the abutment 190 downward out of the path of the tab stops. When the slide 226 is moved to the right in Fig. 8, it is 35 latched in this position by a latch 230 that engages over a stud 231 in slide 226. This latch may be released by an extra long tab stop 185-L (Fig. 8) which engages a pass-by pawl 232 on latch 230 and moves it to released position.

40   When the sensing member 49 is moved down it rocks bell crank 222 clockwise in Fig. 3 which moves link 223 and slide 226 to the right. This sets the skip-tab mechanism as above explained.

From the above, it will be clear that when the 45 sensing member 49 is allowed to move downward by the indexing means in a predetermined column of the carriage, the tabulating mechanism will be conditioned to skip a predetermined number of columns, the return of the tabulating 50 mechanism to normal depending upon the location of the long tab stop 185-L.

Automatic control of repeat machine operations

Another function, or operation, of the machine 55 that is automatically controlled is the number of cycles through which the machine will go without any attention on the part of the operator.

These repeat machine operations are controlled by the sensing member 50 (Fig. 4), which is connected at its upper end to an arm 240 fixed to a shaft 241 pivotally supported on the back plate of the machine. This shaft has another arm 242 fixed to it and extending upwardly as 60 shown most clearly in Fig. 1. The arm 242 has a stud 243 on its upper end positioned over one end of the lever 244 fixed to a shaft 245. Another arm 246 is fixed to the shaft 245 and the upper end of arm 246 has a yielding connection 65 through spring 247 with a slide 248, said spring 247 also serving to urge arm 246 counterclockwise. The slide 248 is urged to the left, as shown in Fig. 1, by spring 247. The spring 247 is connected to a lug projecting from the upper edge 70 of the slide 248 and to an extension of lever 240 75

above the stud entering the slot in slide 248 so that the spring urges the lever 246 clockwise which urges the slide 248 forwardly. This slide controls the repeat operations of the machine in a manner which is described in detail in 5 Patent No. 1,397,774 and which will be only briefly described here.

When the slide 248 is moved to the right as viewed in Fig. 1, it is positioned under a stud 250 on an arm 251 which is thereby prevented 10 from rocking to its full extent in a clockwise direction. The limited movement of the arm 251 prevents a pass-by pawl 252 on its end from acting on a stud 253 on the end of a pivoted 15 lever 254 which is normally rocked near the end of a cycle of operation of the machine to release depressed keys and engage a slide 255 to release the motor bar which has been latched by a latch 256. When the pass-by pawl 252 is prevented 20 from acting as just mentioned, the keys will not be released and the motor bar will remain depressed to cause the machine to take another cycle of operation.

25   In positions of the indexing means where the sensing member 50 is not allowed to move downward, the repeat slide 248 remains in the position of Fig. 1 and the machine is conditioned to be given only a single cycle of operation. If, however, in a predetermined column, the sensing member 50 is allowed to drop, the arms 240 and 242 (Fig. 1) are moved counterclockwise, which rocks arms 244 and 246 to move slide 248 to the right (Fig. 1) to condition the machine for repeat operations. Accordingly, in any desired 30 columnar position of the carriage, repeat operations can be caused to take place automatically 35 by having the proper abutment stop 44 positioned on the indexing means.

It will be recalled that the motor control link 83 is normally latched against movement by the 40 lever latch 100 (Fig. 1), and this latch is returned to normal at the end of each cycle of machine operation. Means must be provided to disable this latch for repeat operations. Referring to Fig. 4, it will be recalled that the latch 75 is controlled by the link 93 which, in turn, is moved by the bell crank 90-92. When the link 98 is moved upwardly from the position of Fig. 4, the bell crank 90-92 is moved to release latch 75 whereupon the bail 55 moves down and this 50 releases certain parts that release the latch lever 100 which moves out of the path of link 83. When the bail 55 is restored to normal during the machine cycle, the latch 100 is restored to 55 normal to block link 83.

Referring to Fig. 4 the bell-crank lever 90-92 carries a pass-by pawl 260 adapted to be engaged by one arm 261 of a yoke 262 pivoted at 263. This yoke has another arm 264 engaging a shaft 265 carried by arms 266 fixed to one of the main drive shafts 146 of the machine. The shaft 146 is first rocked clockwise from the position of Fig. 4 and then returned counterclockwise during a cycle of machine operation. The yoke 262 is normally prevented from moving by means of a latch 268 having a lateral lug 269 engaging over a projection 270 on the yoke, the latch being urged counterclockwise as viewed in Fig. 4 by a spring 271. During a normal operation of the machine, as the shaft 146 rocks clockwise, the shaft 265 moves away from the arm 264, but the yoke 262 does not move because it is held by the latch 268. However, when the machine is conditioned for repeat operations, it will be recalled that the sensing member 50 is moved downwardly which

rocks the shaft 241 counterclockwise. This shaft carries a projection 273 adapted to engage a stud 274 on the latch 268 in such a way that, when the sensing member 50 moves downwardly, the 5 latch 268 is moved to a position to release yoke 262. Accordingly, during that cycle of machine operation, the yoke 262 will be rocked counterclockwise by its spring 275. During this movement, the arm 261 will pass the pass-by pawl 10 260 but, during the return movement of the yoke, caused by the return movement of shaft 265, the arm 264 will engage the pass-by pawl 260 and rock the bell crank 90-92 clockwise to enable it to move to a position to grasp latch 75. 15 The bell crank 90-92 can be rocked clockwise by arm 261 even though link 88 is held upward by the latched-down motor bar. This is due to the stud and slot connection between said bell crank and the link 88. When said bell crank 20 is rocked by the arm 261, the action is only momentary, after which arm 261 passes over pawl 260 and releases the bell crank, whereupon the spring 89, which was tensioned by the clockwise rocking of bell crank 90-92, rocks said bell 25 crank counterclockwise, thereby pulling the link 93 to the right (Fig. 4) and releasing the latch 75. This permits bail 55 to move down a second time to release the sensing members. In other words, near the end of the machine cycle, the 30 general operating means of the machine, that is, the main shaft 146 with its arm 266, causes a release of the bail 55 to enable the sensing members to move to sensing position again and to disable latch 100 for the motor control link 35 83 so that the latter may move upward to cause a repeat operation of the machine.

It is not desired under any circumstances to cause a repeat operation of the machine until after the paper carriage has reached the column 40 intended for such operation. An interlock has been provided to prevent this.

Referring to Fig. 3, the machine is provided, as previously explained, with a dash pot cushion 217 for the tabulating mechanism as described in detail in Muller Patent No. 1,942,216. When one 45 of the tab stops 185 strikes the abutment 190, the latter is moved to the right as viewed in Fig. 3 against the cushioning action of the dash pot above mentioned. When the abutment is disengaged from the active tab stop, the spring 216 (Fig. 3) which is connected to lever 214 that, in turn, is connected to the link 213 (Fig. 8) which carries the abutment, moves the abutment to the left in Fig. 8.

50 The link 213 is provided with an extension 280 (Fig. 8) which engages the upper end of a pawl 281 pivoted at 282 and urged counterclockwise by a spring 283. The lower end of this pawl is adapted to move over the end of one arm of the bell crank 90-92 (Fig. 4) that controls the release of the latch 75 which controls the release of bail 55 that controls the release of the latch 100 for the motor control link 83.

When a tab stop is against the abutment 190, 55 the pawl 281 is rocked clockwise out of alignment with the lever 90, but, when the abutment is released of the tab stop, the link 213 moves to the left and swings the pawl 281 counterclockwise. The pawl cannot move over the lever immediately because the lever is still in its upward position, but the pawl moves against the side of the lever ready for action. As soon as the lever 60 90 is moved downwardly, as it is during the latter part of the cycle of machine operation, the pawl 281 moves over the lever to prevent upward

movement of it to release the latch 75 until the carriage reaches the column it is to occupy whereupon the tab stop engages the abutment 190 and the movement of the latter to the right (Fig. 8) swings the pawl 281 clockwise out of position, thereby releasing the lever 90 which immediately moves to release the latch 75, thereby releasing the motor control link to permit it to give the machine a second cycle of operation.

From the descriptions just given, it will, therefore, be apparent that the repeat machine operations can be controlled automatically in the same manner as other functions of the machine through its sensing member 50, suitable interlocks and controls being provided to insure that the operation will take place properly.

Special control of carriage

When the machine is conditioned for and operated to perform a certain sample of work to 20 be presently described, the paper carriage is caused to return automatically after a repeat operation of the machine.

Referring to Fig. 1, the machine is provided with a special motor bar 300. One arm of a bell crank 301 pivotally carried on the stem 297 of the special motor bar 300 has a slotted end engaging a stud 299 on the lever 80 with which the regular motor bar is connected. The other arm of the bell crank 301 cooperates with a 25 fixed stud 302. When the main motor bar is depressed alone, the lower arm of the bell crank 301 is rocked to a position over the stud 302 and prevents subsequent depression of the special motor bar 300 while the regular motor bar remains depressed. When the special motor bar 300 is depressed, a hook 298 on the stem of said motor bar engaging over the stud 299 causes the regular motor bar also to be depressed and latched down by the latch 256. The lower arm 30 of the bell crank simultaneously moves down behind the stud 302 and, in cooperation with said stud, holds the special motor bar 300 down while the regular motor bar 11 remains down. The stem of the special motor bar is connected to 40 one arm of a bell crank 303 urged clockwise as viewed in Fig. 1 by a spring 304. The other arm of this bell crank is positioned over a stud 305 on one arm of a three-arm member 306 pivoted at 307 and urged clockwise by a spring 308. The upper arm of this three-arm member contacts a stud 309 on a plate 310 connected to the drive shaft 311 which is first rocked counterclockwise from the position of Fig. 1 during a machine cycle and then returned clockwise. The lower 45 arm of the three-arm member 306 carries a stud 312 adapted to cooperate with a pass-by pawl 313 pivoted on one arm of a pivoted bell crank lever 314.

When the special bar 300 is depressed, the bell 50 crank 303 is rocked counterclockwise which frees the stud 305 and allows the three-arm member 306 to move clockwise under the urge of its spring 308 as the stud 309 is rocked counterclockwise during the machine cycle. During this movement of the three-armed lever, the stud 312 passes the pawl 313. Upon the return or counterclockwise movement of the three-armed lever 55 306, caused by the engagement of the stud 309 with it, the stud 312 engages the pass-by pawl 70 313 and rocks the bell crank 314 clockwise.

The bell crank 314 is connected at its lower end to a link 315 which, in turn, is connected to an arm 316 fixed to a shaft 317. This shaft carries another arm 318 connected to one end of a

lever 319 pivoted at 320. The rear end of this lever is connected to a link 321 which, when the bell crank 314 is moved clockwise as above explained, is pulled downwardly.

- 5 Referring to Fig. 9, when the link 321 is pulled downward, it moves a slide 322 downward which releases a pivoted latch 323. Latch 323 releases a slide 324 which is thereupon moved upwardly by a spring 325 to rock a lever 326 clockwise about its pivot 327 to throw in the carriage return clutch 328. The carriage return mechanism is thus automatically conditioned during the return stroke of the machine to return the carriage toward its original position. This return 10 movement continues until a cam 330 on the carriage engages a stud 331 on the slide 324 and moves it downwardly to rock the lever 326 counter clockwise to disengage the carriage return clutch.
- 15 20 Accordingly, if, at any time, the operator depresses the special motor bar 300, the paper carriage will be automatically returned toward normal and stopped in a predetermined column depending upon the location of the cam 330.
- 25 When the special motor bar 300 is depressed while the paper carriage is in a columnar position where it conditions the machine for an automatic repeat operation the above described parts are conditioned differently than above stat- 30 ed. It will be remembered that the carriage conditions the machine for an automatic repeat cycle by rocking the lever 246 (Fig. 1) clockwise. Connected to the lower end of this lever is a link 340 which, in turn, is connected to a pivoted 35 latch 341 having a lateral lug on its end adapted to move under the upper arm of the three-armed lever 306.

Thus, if the special motor bar 300 is depressed while the carriage is in a columnar position where 40 it conditions the machine for an automatic repeat operation following the cycle initiated while the carriage is in said position, the return mechanism is disabled and remains disabled as long as the machine remains in automatic repeat cycle 45 condition. However, when the carriage comes to rest in the column where the last automatic repeat cycle is to be performed, that is, a columnar position immediately preceding one where a cycle must be initiated manually, the lever 246 50 and slide 248 return to normal and the carriage return mechanism will operate automatically at the end of said automatic repeat cycle of the machine.

Accordingly, even though the special motor 55 bar 300 is depressed in the No. 1 column, the three-armed lever 306 cannot rock clockwise under the urge of its spring 308 and the carriage return mechanism is not conditioned for operation. In the No. 1 column, the machine is also 60 conditioned to automatically skip to the No. 3 column and, since the repeat mechanism is conditioned for operation in No. 1 column, the carriage will move to its No. 3 column after the cycle in column No. 1, and the machine will then be 65 automatically given a cycle of operation in column 3. In this column, the repeat mechanism is not conditioned for operation, and hence the above-mentioned special control of the carriage return mechanism becomes operative so that, 70 after the repeat operation in the No. 3 column, the carriage is automatically returned to the No. 2 column. In the latter column the repeat mechanism is not active but the skip tab mechanism is. The machine is given a cycle in column 2 by depressing the regular motor bar and, after

the cycle, the machine stops and the carriage tabulates to its No. 4 column, column 3 being skipped. An adjustment of a long stop 185L such that it will cause the carriage to be arrested in column 3 when it skips from column 1 to column 3 but not when it tabulates after an operation in column 2 is obtainable by virtue of the movement which the abutment 190 is permitted before it arrests the carriage after it has been engaged by a tab stop 185. Said long stop 10 185L can be so positioned that when the carriage is at rest in column 2 said long stop will be to the right of the latch pawl 232 as viewed in Fig. 2, but it will operate on the pawl 232 to trip the latch just too late to arrest the carriage in column 2 but quite early enough to arrest the carriage in column 3 when the carriage moves from column 1 with the skip-tab mechanism in skip- 15 ping condition.

Normalizing features

20

It is possible to normalize both the tabulating mechanism and the repeat mechanism together, or to normalize the repeat mechanism separately.

Referring to Fig. 1, a normalizing key 350 is 25 mounted on the keyboard, the key being latched in the usual manner after being depressed. The stem 351 of this key is slidably mounted on a stud 352 and the stem has a rear projection 353 carrying a stud 354 which, when the key is de- 30 pressed, rocks a pivoted lever 355 (Fig. 3) clockwise. The center of this lever is connected to a link 356 which has a bent end 357 (Fig. 8) that disables the tabulating pawl 192. In other words, when the normalizing key 350 is depressed, 35 the tabulating pawl 192 is disabled so that the tabulating mechanism will not be operated during a cycle of machine operation.

The stem 351 of the normalizing key also has a forward projection 360 adapted to engage a 40 stud 361 on a lever 362 pivoted on the stud 352. The rear end of this lever carries a stud 363 adapted to engage the arm 244 connected to the shaft 245 that controls the repeat lever or arm 246. When the normalizing key 350 is depressed, 45 the lever 362 is rocked counterclockwise, which rocks the repeat lever 246 counterclockwise, or prevents clockwise movement of it, so that repeat machine operations are prevented.

When it is desired to normalize the repeat 50 mechanism only, another normalizing key 370 is depressed, this key being also latched after being depressed. The lower end of the stem of this key is connected to an arm 371 pivoted on the shaft 245. This arm has a lug 372 adapted to 55 be positioned to the rear of a stud 373 on the repeat slide 248. Accordingly, when the normalizing key 370 is depressed, the repeat slide 248 cannot move to the right in Fig. 1, and the machine cannot be conditioned for repeat machine 60 operations. The normalizing key 370 has no connection with the tabulating mechanism and hence its depression normalizes the repeat mechanism only.

Sample of work

65

A sample of work of which the machine is capable is shown in Fig. 11. For this work the machine is conditioned and functions as follows:

In the No. 1 columnar position of the carriage, the special motor bar 300 is depressed. The sensing member for the main register is allowed to move downward, upon downward movement of the regular motor bar, to "non-add" the main register. The sensing members for the multiple 75

registers do not move and these registers remain in "non-add" condition. The sensing member for the tabulating mechanism is allowed to move downward to condition the tabulating mechanism to cause the carriage to skip the No. 2 column. The sensing member for repeat machine operations is allowed to move down to condition the machine for repeat operations. The machine is given a cycle of operation during which the item that is entered on the amount keys is printed but not entered in any of the registers. During the latter part of this cycle, the carriage automatically moves to its No. 3 column, column No. 2 being skipped.

When the carriage arrives at its No. 3 column, it is automatically given a cycle of operation owing to the fact that the repeat machine mechanism has been conditioned as just explained. This cycle does not start, however, until after the carriage has reached this position, owing to the interlock previously described. In this position of the carriage, the sensing member for the main register is allowed to move to condition the latter for subtraction so that the item is subtracted from this register, and the sensing members for the multiple registers are allowed to move to the "add" position so that the item is added in each of the latter registers. The repeat machine operation sensing member is not moved, with the result that a third operation of the machine will not take place. Accordingly, during this second cycle of operation, the item will be subtracted from the main register, it will be added in each of the multiple registers, and, at the end of the operation, the carriage will be automatically returned to its No. 2 column, a cam 330 (Fig. 9) being provided to arrest the carriage in this position.

The machine then stops, whereupon the operator makes another entry on the amount keys, after which he depresses the regular motor bar. In this position of the carriage, the sensing member for the main register is allowed to move to "non-add" the latter and the sensing members for the multiple registers do not move so that no addition occurs in either of them. The sensing member controlling the tabulating mechanism is conditioned to cause the carriage to skip the No. 3 column. At the end of the cycle of operation, the carriage automatically moves to its No. 4 column. The sensing member for the repeat operations is allowed to move in column 2 and then continues to move in columns 4 and 5 so that the machine operates automatically in columns 4, 5 and 6, after which it is automatically returned to the right, viewing the machine from the front, and machine operations stop. In columns 4 and 5 all the registers are non-added, while in column 6 all of them in "add" condition.

The above operations are particularly useful in connection with certain types of public utility billing where certain of the items are to be repeated, but it is to be understood that the machine can be conditioned for many other types of work by varying the controls heretofore described.

It is to be understood that the construction shown is for purposes of illustration only and that variations may be made in it without departing from the spirit and scope of the invention as defined by the appended claims. The claims on the broad subject matter of the sensing type of automatic controls have been transferred to my copending application Serial No. 51,263, filed November 23, 1935.

I claim:

1. A machine of the class described having means for giving it cycles of operation, a traveling paper carriage, a tabulating mechanism for controlling the columnar positioning of said carriage, means for operating said tabulating mechanism to cause it to release said carriage early in a cycle of operation of said machine, holding means other than said tabulating mechanism for holding said carriage against movement when so released, function conditioning means for said machine movable to active position and restorable to normal, means for restoring said function conditioning means to normal later during the cycle of machine operation, and means operated by said restoring means for moving said carriage holding means to release said carriage at the time said function conditioning means is restored to normal.

2. A calculating machine of the class described having calculating mechanism, means for giving said machine cycles of operation, a traveling paper carriage normally movable from column to column across the machine as an incident to each machine cycle, a tabulating mechanism controlling said movements of said carriage, function-indexing means indexed automatically in accordance with the position of said carriage, a plurality of function-controlling devices normally out of engagement with said indexing means but automatically movable into engagement therewith sufficiently prior to operation of the calculating mechanism of said machine to control the functions of said machine during the machine cycle, means for operating said tabulating mechanism to release said paper carriage for movement early in the machine cycle, holding means operated automatically as said function-controlling devices are moved into engagement with said indexing means to temporarily hold said carriage against movement, and means operating during said machine cycle to restore said function-controlling devices to their normal position out of engagement with said indexing means and to also release said carriage holding means to thereby enable said carriage to move to its next position without interference from said function-controlling devices.

3. A calculating machine of the class described having means for giving it cycles of operation, a paper carriage normally movable in one direction from one columnar position to the next adjacent position as an incident to each machine cycle, carriage-return means for returning said carriage in the opposite direction, control means operable in predetermined positions of said carriage, means conditioned by operation of said control means for causing said carriage return means automatically to return the carriage in the opposite direction during the machine cycle effected after operation of said control means, repeat means automatically conditioned in at least one of said predetermined carriage positions to cause said cycling means to give the machine an automatic cycle when the carriage reaches a subsequent columnar position and to hold said control means, when operated in the said predetermined carriage position, in operated condition until said automatic cycle is effected, and means rendered effective by said repeat means, when the latter is so conditioned, to prevent operation of said carriage return means until said automatic cycle is performed in said subsequent carriage position.

4. A calculating machine of the class described having means for giving it cycles of operation, a travelling paper carriage, tabulating mechanism normally controlling said carriage to cause it to move from one column to the next adjacent column during the latter part of a machine cycle, indexing means indexed in accordance with the columnar positions of said carriage, "skip-tab" mechanism for conditioning said tabulating mechanism to cause said carriage to skip predetermined columns, sensing means operable to sense said indexing means, and means for causing said sensing means to sense said indexing means at the beginning of a machine cycle to condition said "skip-tab" mechanism to enable said carriage, when the tabulating mechanism operates, to skip to a predetermined column in the latter part of said machine cycle.
5. A calculating machine of the class described having means for giving it cycles of operation, a travelling paper carriage, tabulating mechanism normally controlling said carriage to cause

it to move from one column to the next adjacent column during the latter part of a machine cycle, indexing means indexed automatically in accordance with the columnar positions of said carriage, a "skip-tab" mechanism for conditioning said tabulating mechanism to cause said carriage to skip predetermined columns, sensing means adapted to be moved into sensing engagement with said indexing means, means for causing said sensing means to sense said indexing means for a given machine cycle to condition said "skip-tab" mechanism to release said carriage for movement, and holding means conditioned automatically as said sensing means is moved to sensing position to temporarily hold said carriage against movement, said holding means being automatically released as said sensing means is moved out of sensing engagement with said indexing means to thereby enable said carriage to skip to a predetermined column.

ROBERT L. MULLER.
